CLAIM

The ornamental design for an amount display housing for cash register or the like, substantially as shown.

DESCRIPTION

FIG. 1 is a left front perspective view of an amount display housing for cash register or the like showing our new design;

FIG. 2 is a front elevation view thereof;

FIG. 3 is a rear elevation view thereof;

FIG. 4 is a left side elevation view thereof, the right being a mirror image of the left side; and

FIG. 5 is a top plan view thereof.
